RECHARGEABLE FLASHLIGHT

Ian A. Tesar, Eastchester, N.Y., assignor to Herbert J. Ashe, ½ H. J. Ashe Company, Inc., South Norwalk, Conn.

Filed Mar. 6, 1967, Ser. No. 6,085

Term of patent 14 years

(Cl. D48—24)

FIG. 1

FIG. 2

FIG. 4

FIG. 3

FIG. 5

FIG. 7

FIGURE 1 is a perspective view showing the front, one side and a portion of the top of a rechargeable flashlight embodying my new design;

FIGURE 2 is a top plan view thereof;

FIGURE 3 is a side elevational view thereof along line 3—3 in FIGURE 2;

FIGURE 4 is a front elevational view thereof along line 4—4 in FIGURE 3;

FIGURE 5 is a rear elevational view thereof along line 5—5 in FIGURE 3;

FIGURE 6 is a bottom plan view thereof along line 6—6 in FIGURE 3; and

FIGURE 7 is an elevational view thereof along line 7—7 in FIGURE 6, showing the side opposite to the one shown in FIGURE 3.

I claim:

The ornamental design for a rechargeable flashlight, substantially as shown.
